CLAIM

The ornamental design for a vehicle charger, as shown and described.

DESCRIPTION

FIG. 1 is a perspective view of a vehicle charger showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The claimed design is indicated by the relative dark portions in the drawings, while the relative light portions enclosed by broken lines are portions of the vehicle charger that form no part of the claimed design.

Shading is used to illustrate the curvature of the part and not color.
